A. H. McMASTER

ENGINE POWER INCREASING DEVICE

Filed June 23, 1924.

INVENTOR.
Arthur H. McMaster
By Martin P. Smith, ATTY.

UNITED STATES PATENT OFFICE.

ARTHUR H. McMASTER, OF LOS ANGELES, CALIFORNIA.

ENGINE-POWER-INCREASING DEVICE.

Application filed June 23, 1924. Serial No. 721,787.

To all whom it may concern:

Be it known that I, ARTHUR H. McMASTER, a citizen of the United States, residing at Los Angeles, in the county of Los Angeles and State of California, have invented certain new and useful Improvements in Engine-Power-Increasing Devices, of which the following is a specification.

My invention relates generally to engines, and more particularly to a device that is applicable to practically all forms of fluid pressure engines having reciprocating pistons, the purpose of said device being to materially increase the power that is developed by the engine with which said device is associated. My present invention is an improvement on the engine power increasing devices forming the subject matter of my co-pending applications for U. S. Letters Patent filed April 30, 1923, and bearing the Serial Numbers 635,808 and 635,809.

The principal objects of my present invention are to generally improve upon and simplify the construction of the devices disclosed in my aforesaid co-pending applications, as well as other forms of similar devices, to provide a relatively simple, practical, strong and durable power increasing device that may be advantageously employed in connection with internal combustion engines, steam engines or, in fact, any engine having a reciprocating piston that is acted upon by the expansion of fluids or by the ignition and combustion of gases, liquid hydrocarbon, pulverized coal dust, powder or other similar explosive substances.

My invention contemplates a device that functions as a pitman or connecting rod between the crank shaft and piston of the engine, which device in operation enables the piston to remain stationary for a substantial period of time at the inner end of its stroke or while at "high center" and while the crank to which said piston is connected is traveling approximately 90° through the upper portion of its circular path of travel, thus making it possible to obtain the maximum degree of power from the expansive forces of the fluid pressure that is admitted to or ignited within that portion of the combustion chamber above the piston.

With the foregoing and other objects in view, my invention consists in the features of construction, combination and arrangement of parts hereinafter more fully de-

scribed and claimed, reference being had to the accompanying drawings, in which—

Figure 1 is a vertical section taken lengthwise through the center of an engine cylinder having a reciprocating piston and showing my improved power increasing device applied thereto;

Figure 2 is a vertical section taken on the line 2—2 of Figure 1;

Figure 3 is a vertical section similar to Figure 1 showing a modified form of the engine power increasing device;

Figure 4 is a vertical section taken on the line 4—4 of Figure 3.

Referring by numerals to the accompanying drawings, and particularly to the form of device illustrated in Figures 1 and 2, 10 designates an engine cylinder, 11 the piston that is arranged for operation within said cylinder, 12 the spark plug or ignition device that is seated in the head of the cylinder, and 13 the crank shaft that is associated with the engine, and which is provided with a crank such as 14 for each cylinder. My invention contemplates a wrist pin 15 having its ends seated in the wall of piston 11 and the intermediate portion of said wrist pin is provided with a pair of cranks 16 and 17 that are arranged diametrically opposite to each other or 180° apart.

A connecting rod or pitman 18 connects the crank 16 of the wrist pin with crank 14 of the crank shaft 13, and connected to crank 17 of the wrist pin is one end of an auxiliary connecting rod 19 that extends alongside of the greater portion of connecting rod 18. A pin or bolt, such as 20, passes through a longitudinally disposed slot 21 that is formed in the lower portion of connecting rod 18, and said pin is rigidly seated in the lower portion of the auxiliary connecting rod 19. The lower or outer end of auxiliary connecting rod 19 is provided with a substantially T-shaped slot 22 that receives a guiding rail or bar 23 that is substantially T-shaped in cross section and which is carried by the lower or outer ends of a pair of oppositely arranged arms 24 that project outwardly from the skirt portion of the piston 11. This guide bar occupies a position at right angles to the axis of the crank shaft and substantially parallel with the plane of travel of the crank 14, and one-half of the length of said guide bar is curved upward, as designated by 26, so that one

end of said guide bar is positioned a short distance above the other.

This arrangement is used where the crank shaft of the engine always travels in the same direction, but for a reversible engine, for instance, an engine that is operated by steam, then both ends of the guide bar are curved upwardly from the center, as illustrated by dotted lines in Figure 1.

- 10 During the operation of the engine, with which my improved device is associated, piston 18 in its travel vibrates or swings alongside the guide bar 25, and as such movement takes place the lower end of the auxiliary connecting rod 29 slides lengthwise upon the guide bar, due to the engagement of the slotted lower end thereof with said guide bar. As crank 14, which travels in the direction indicated by the arrow in Figure 1, approaches an angular position approximately 45° in advance of high center position of the piston, the lower end of auxiliary connecting rod 19 is traveling on the approximately straight lower portion of bar 25, and as crank 14 passes from this position to high center the auxiliary connecting rod 19 will, through its connection with crank 17, rock the wrist pin 15 so as to raise crank 16, to which connecting rod 18 is connected, and as a result, piston 11 will maintain a practically stationary position at its high center or while the crank is passing from a point approximately 45° in advance of high center to a point approximately 45° past high center. During this time the compressed gaseous fuel charge is held under maximum compression, and said compressed charge is not fired until the crank and connecting rod are substantially "out of toggle" or at a point approximately 45° past high center. As the lower end of auxiliary rod 19 passes on to the curved portion 26 of the guide rail, said auxiliary rod commences to move upward, thereby swinging crank 17 to its upper limit of movement and, consequently, swinging crank 16 to its downward limit of movement, such action taking place during the travel of the crank from its high center position to a point approximately 45° past high center. This relative movement of the pistons is permitted by reason of the fact that pin 20 which is seated in the auxiliary connecting rod is arranged so as to slide freely through slot 21 in the main connecting rod 18. When crank 14 has reached a point approximately 45° past high center, the compressed gaseous fuel charge above the piston is ignited and the expansion following combustion drives the piston downward on its power stroke and during the downward swinging movement of the crank 14 and the upward movement thereof to a point approximately 45° in advance of high center, the two connecting rods, the pistons and wrist pin all move as one part.
- 15 In the modified construction illustrated in Figures 3 and 4, wrist pin 27 is provided with an eccentric 28 that receives the upper end of main connecting rod 29, the lower end of the latter being connected to crank 30 of crank shaft 31, and the upper end of auxiliary connecting rod 32 is connected to a crank 33 that is formed on the wrist pin to the side of the eccentric 28, which crank 33 is radial with respect to the axis of the wrist pin. In this form of the device the lower end of the auxiliary connecting rod has sliding connection with a guide bar 34 that is carried by extension arms on the piston of the engine, and the main and auxiliary connecting rods have a pin-and-slot connection similar to the pin-and-slot connection between rods 18 and 19. Guide bar 34 has an upwardly curved portion 35 and, as in the previously described construction, when the lower end of auxiliary connecting rod 32 travels on to this upwardly curved end portion of the guide rail, the upward swinging movement of crank arm 33 moves eccentric 28 downward, thereby enabling the piston with which the device is associated to remain stationary while the crank 30 is traveling through the upper portion of its path of travel or from a point approximately 45° in advance of high center to a point approximately 45° past high center.
- 20 While I have shown and described my improved device as being particularly designed for use in connection with internal combustion engines, it will be understood that practically the same structure modified to suit conditions may be advantageously employed on practically all types of reciprocating piston engines, which are operated by steam, compressed air, crude oil, or by the practically instantaneous combustion of pulverized coal or the like. Thus it will be seen that I have provided relatively simple, practical and efficient means for materially increasing the effectiveness of fluid pressure engines, the mechanism employed being of such structure as to be easily and cheaply produced and readily installed.
- 25 It will be understood that minor changes in the size, form and construction of the various parts of my improved engine power increasing device may be made and substituted for those herein shown and described without departing from the spirit of the invention, the scope of which is set forth in the appended claims.
- 30 I claim as my invention:
1. In an engine, the combination with the piston thereof, and the crank shaft, of a wrist pin mounted in the piston and having a pair of bearing portions that are offset relative to the axis of said wrist pin, a main connecting rod arranged between one of said bearing portions and the crank shaft, an

auxiliary connecting rod connected to the other bearing portion of said wrist pin and means carried by the piston and serving as a guiding bearing for the outer portion of said auxiliary connecting rod.

2. In an engine, the combination with the piston thereof, and the crank shaft, of a wrist pin mounted in the piston and having a pair of bearing portions that are offset relative to the axis of said wrist pin, a main connecting rod arranged between one of said bearing portions and the crank shaft, an auxiliary connecting rod connected to the other bearing portion of said wrist pin, means carried by the piston and serving as a guiding bearing for the outer portion of said auxiliary connecting rod and a pin and slot connection between the main and auxiliary connecting rods.

3. In an engine, the combination with the piston thereof and the crank shaft, of a wrist pin journalled in the piston and provided with a pair of cranks that are arranged substantially opposite to each other, a main connecting rod arranged between one of said cranks and the crank shaft, an auxiliary connecting rod connected at its inner end to the other crank of the wrist pin, and a guide bar carried by the piston and with which the outer end of the auxiliary connecting rod engages.

4. In an engine, the combination with the piston thereof and the crank shaft, of a wrist pin journalled in the piston and provided with a pair of cranks that are arranged substantially opposite to each other, a main connecting rod arranged between one of said cranks and the crank shaft, an auxiliary connecting rod connected at its inner end to the other crank of the wrist pin, a

guide bar carried by the piston and with which the outer end of the auxiliary connecting rod engages and the two connecting rods having sliding pivotal connection with each other.

5. An engine power increasing device comprising a wrist pin for the piston of the engine, which wrist pin is provided with a pair of eccentrically arranged bearing portions, main and auxiliary connecting rods connected respectively to said bearing portions, the main connecting rod being connected to the crank shaft of the engine and a guiding bearing for the outer portion of said auxiliary connecting rod.

6. An engine power increasing device comprising a wrist pin for the piston of the engine, which wrist pin is provided with a pair of eccentrically arranged bearing portions, main and auxiliary connecting rods connected respectively to said bearing portions, the main connecting rod being connected to the crank shaft of the engine, a guiding bearing for the outer portion of said auxiliary connecting rod and the outer portions of said connecting rods having sliding pivotal connection.

7. The combination with an engine piston and crank shaft, of a wrist pin mounted in said piston and having an eccentrically arranged bearing portion, a rod connected to said bearing portion and said crank shaft and means associated with said wrist pin and rod for rocking said wrist pin to shift the position of the bearing portion thereon during a predetermined portion of each complete rotation of said crank shaft.

In testimony whereof I affix my signature.

ARTHUR H. McMASTER.
